(57) **CLAIM**

The ornamental design for a cosmetic dispenser, as shown and described

DESCRIPTION

FIG. 1 is a perspective view of a cosmetic dispenser according to one implementation;

FIG. 2 is a front elevation view of the cosmetic dispenser of FIG. 1;

FIG. 3 is a right side elevation view of the cosmetic dispenser of FIG. 1;

FIG. 4 is a top plan view of the cosmetic dispenser of FIG. 1;

FIG. 5 is a back elevation view of the cosmetic dispenser FIG. 1;

FIG. 6 is a left side elevation view of the cosmetic dispenser of FIG. 1; and,

FIG. 7 is a bottom plan view of the cosmetic dispenser of FIG. 1.

The broken line showing in FIG. 7 is for illustrative purposes only, and forms no part of the claimed design.
